UNITED STATES PATENT OFFICE.

BRUCE M. STANNARD AND WILLIAM K. BISHOP, OF BINGHAMTON, NEW YORK, ASSIGNEES TO THE BREWER-TITCHENER CORPORATION, OF CORTLAND, NEW YORK, A CORPORATION OF NEW YORK.

CURTAIN-ROD CAP.

Application filed June 4, 1924. Serial No. 717,793.

To all whom it may concern:

Be it known that we, BRUCE M. STANNARD and WILLIAM K. BISHOP, citizens of the United States, and residents of Binghamton, and county of Broome and State of New York, have invented certain new and useful Improvements in a Curtain-Rod Cap, of which the following is a specification.

Our invention relates to improvements in a protector hood for vehicle curtain rod supports, particularly for such curtains as are commonly used in connection with an open or touring type of automobile and in which an upright rod support for the curtain is removably mounted in a socket located near the outer edge of door rail and adapted to swing with the opening and closing of the door. The present improvements are more especially directed toward a simple but effective means for protecting the curtain fabric against wear and preventing the upper end of the supporting curtain rod from puncturing or otherwise defacing the fabric.

The object of this invention is to provide an intermediary blunted abutment element for the end portion of the supporting rod, which element bears against and is adapted to carry the weight of the side curtain. In the preferred embodiment, our reenforcing means comprises a supplementary dished hood for the rod cap made of stamped sheet metal having an integral clip or socket part disposed normally to the longitudinal dimension of the hood and adapted to snap over the end of the supporting rod and if preferred may be swivelly mounted thereon. The cap hood is kept relatively short and when attached to the rod end, this protector member together with the rod freely enter and pass up through the stitched or hemmed sheath formed adjacent to the vertical or swinging edge of the door curtain. The upper end portion of this sheath is provided with a closed or blinded end against which our rod protector hood is intended to thrust. The rod end reenforcement is therefore entirely concealed within said curtain pocket while the hood portion of the cap is well rounded and enlarged with respect to the transverse section of the rod end whereby the bearing surface thrusting upward against the blinded end of the curtain pocket is materially augmented.

Embodying herein are also other features of structure designed to facilitate the manufacture and application of said rod caps for the purpose intended, all of which will be set forth in detail hereinafter.

Reference is had to the accompanying one sheet drawing which illustrates an example of the preferred form of our invention; like characters of reference indicate like parts in the several views, and in which drawing:

Fig. 1 is a partial perspective of an automobile body having a door and side curtain therefor equiped with our improvements.

Fig. 2 is a detailed view in section of the assembled rod and curtain members as taken along line 2-2 of Fig. 1.

Fig. 3 represents an enlarged elevational side view of our elongated rod cap seen in Fig. 1, said cap being disengaged from its rod end.

Fig. 4 is an enlarged end view of the rod cap as seen in Fig. 2.

Fig. 5 shows a sectional detail of the rod cap as taken along line 5-5 of Fig. 4.

Fig. 6 is a sectional end view showing the clip socket of our device snapped over the end of the curtain rod into its operative position and is here shown as swivelly mounted thereon.

Fig. 7 shows a bottom view of Fig. 3.

Fig. 8 represents the blank from which our rod cap is formed up.

Fig. 9 shows a circular instead of elongated cap and also a modified method of fastening the cap to the rod end which is here permanently attached thereto.

Fig. 10 represents a bottom view of Fig. 9.

Referring first to Fig. 1, the letter A represents the side curtain in its entirety, the lower edge of which curtain is mounted along and overlaps the top rail B₁ of the hinged side door B₂. The hinged or attached vertical edge of the curtain A may be buttoned in the position shown by any suitable curtain fasteners such as A₁ while the outer or swinging vertical edge of said curtain that opens with the door, is supported and stiffened by the curtain rod C₁. The lower end of the rod C₁ may be mounted in a rod socket B₃ as set into the horizontal face of the top door rail B₁ in the conventional manner.

The transparent side curtain A is preferably made of suitable sash fabric A₂ having its outer free or swinging edge portion in-turned or otherwise provided with an adjacent hemmed rod sheath A₃, the vertical stitching of said sheath being represented by dotted lines in Fig. 1. The upper end of said sheath is then closed by stitching or by equivalent means to form a blinded fabric pocket end A₄. The curtain rod is mounted within the sheath A₃ as shown, and intermediate the rod end and the blinded pocket portion A₄, we provide for a reenforcing rod cap D, which cap constitutes an important feature of the present invention.

As is best shown in detail in Fig. 3 and subsequent views, this cap comprises a dished hood member D₁, which consists essentially of an elongated sheet metal structure preferably having the ends thereof rounded inwardly toward the longitudinal axis X—X as shown. Formed integral with said hood or protector member D₁ are a pair of depending clip parts D₂, which together form a resilient split socket element of circular contour having its axis Y—Y disposed substantially normal to that of the head axis X—X. These clips are intended to snap together so as to fit snugly over the diameter of the end of the rod C₁.

For the purpose of holding the clip socket in engagement with the rod, it is preferred to provide a rod groove or notch C₂ as is best shown in Fig. 3. When the rod is pushed into the socket parts D₂ as shown in Fig. 6, the groove C₂ registers and engages with the inwardly indented nibs D₃ formed in the cylindrical surface of one or both of the clips D₂. When thus engaged, the top of the rod C₁ is intended to have a small clearance space with respect to the transverse dished hood wall D₁ but the snap engagement of the cap with the rod is intended to be sufficiently stiff to allow these parts to be withdrawn as a unit from the fabric sheath A₃. The described method of snapping the demountable rod cap on or off of the rod has the advantage of cheapness in manufacture and also allows for swivel action between said cap and its supporting rod, but when a permanent tie is desired between these parts, this can readily be accomplished by the use of a through rivet C₃ as indicated in Fig. 9.

Fig. 8 shows the sheet metal blank from which the rod cap is shaped up. The central or body portion of the blank designated as D₁, is stamped to form the described hood part of our cap while the extending leg portions are bent up and rounded off into the cylindrical socket members such as D₂. The longitudinal edges of the complementary clips D₂, running lengthwise of the axis Y—Y are spaced apart somewhat as shown in Fig. 7 and the sheet metal used for mak-

ing the rod cap is intended to possess sufficient resiliency to provide for the desired snap action between said clips.

It will be seen therefore that when the upper end of the curtain supporting rod C₁ is provided with our improved rod cap, the curtain weight will be well distributed over the available fabric surface and there will be little or no tendency for the rod end to wear or tear through the curtain. This latter defect is a common failing with rods not properly reenforced and permits the curtain to wrinkle and sag, besides otherwise disfiguring the curtain and greatly lessening the effectiveness of rod in its supporting function.

The herein described device is designed to overcome this difficulty in an extremely simple and effective manner. It will be evident from the preceding disclosures that the described curtain sheath is to be made wider than the desired length of the cap hood D₁ as measured along the axis X—X, so as to permit the rod and its hood reinforcement to be pushed up into the sheath pocket from below. The rod cap is housed and completely concealed within the upper portion of the curtain sheath and this feature adds materially to the neatness and finished appearance of the door curtain. It will also be apparent that the rod reinforcement may readily be applied even by inexperienced automobile operators and that it is admirably adapted for the purpose intended.

It will be understood the shape of the cap hood can also be made circular instead of elongated and that the described socket parts need not necessarily be formed integral therewith, and that various other changes in the details of our device may be resorted to without departing from the spirit and scope of our invention, heretofore described and more particularly set forth in the appended claims.

Claims:

1. In a vehicle curtain provided with a single substantially straight blinded sheath pocket disposed adjacent to one marginal edge of said curtain, a supporting rod therefor mounted within said sheath and having its end portion abutting the blind end of the sheath, and an intermediary metallic protector cap for the rod end comprising a transversely disposed hood member adapted to thrust against the blinded end of said pocket and a socket member adapted to embrace said rod end, all of said cap members being wholly concealed within the sheath and removable as a unit through the open end thereof.

2. In a vehicle curtain provided with a blinded sheath pocket disposed adjacent to one marginal edge of the curtain, a supporting rod therefor mounted within said sheath and having its end portion abutting the

- blind end of the sheath, and a protector cap concealed within said sheath comprising a transversely disposed hood member attached to said rod and serving to supplement the 5 cross-sectional thrust area of the rod end for the purpose of protecting the curtain fabric against puncture, said cap members together with the rod being removable as a unit through the open end of said sheath.
- 10 3. In a device of the character described, the combination of a curtain of flexible material, having a vertically arranged sheath pocket and an upright support rod located therein, of a supplementary rod cap 15 serving to reenforce said pocket against puncture by the rod end, which cap comprises a transversely disposed protector hood and a socket member formed integral therewith adapted to embrace the rod end, 20 all of which cap elements being concealed within said sheath pocket and removable as a unit with the rod through the open end thereof.
4. In an automobile side curtain having a 25 door curtain adapted to swing with the automobile door, a door rod of which one end is mounted upon and attached to said door, a metallic rod cap comprising a transversely disposed hood and a socket member 30 therefor embracing the free end of the door rod, and a sheath pocket member for the curtain disposed along and serving to enclose the other end portion of the door rod and fully conceal said cap members, said 35 rod together with its cap members being removable as a unit through the open end of said sheath pocket.
5. In a vehicle curtain provided with a blinned sheath pocket, a grooved or notched
- supporting rod therefor mounted within 40 said sheath and having its end portion abutting the blind end of the sheath, a demountable protector cap comprising a hood member adapted to thrust against the blind end of said pocket, a resilient socket for said 45 hood adapted to embrace the rod end, and a nib element for said socket adapted to engage and snap into said rod groove or notch.
6. In a vehicle curtain provided with a 50 blinned sheath pocket, a supporting rod therefor mounted within said sheath and having its end portion abutting the blind end of the sheath, an intermediary metallic cap for the rod end comprising a transversely disposed hood member adapted to 55 thrust against the blind end of said pocket and a socket member for said hood serving to embrace said rod, and means for fastening said socket to said rod, all of said cap 60 elements being concealed within said sheath and removable as a unit through the open end thereof.
7. In a vehicle curtain provided with a blinned sheath pocket, a supporting rod 65 therefor mounted within said sheath and having its end portion abutting the blind end of the sheath, and a separable intermediary metallic protector cap adapted to embrace said rod end and having a hood 70 member disposed crosswise to the rod axis, said hood being larger than the rod diameter and removable as a unit with the rod through the open sheath end.

In testimony whereof, we have signed our 75 names to this specification.

BRUCE M. STANNARD.
WILLIAM K. BISHOP.
